DESIGN FOR A COMBINATION REFRIGERATOR AND FOOD FREEZING UNIT

Alfred O. Boyce, Minneapolis, Minn., assignor of one-third to Helen A. Downing, Minneapolis, Minn.

Application March 6, 1946, Serial No. 127,172

Term of patent 14 years

(Cl. D67—3)

To all whom it may concern:

Be it known that I, Alfred O. Boyce, a citizen of the United States and residing in the city of Minneapolis, county of Hennepin, State of Minnesota, have invented a new, original, and ornamental Design for a Combination Refrigerator and Food Freezing Unit, of which the following is a specification, reference being made to the accompanying drawing, forming a part thereof, wherein:

Fig. 1 shows a perspective view of a combination refrigerator and food freezing unit showing my new design with the upper and lower doors in closed position and the center doors in open position.

Fig. 2 shows a front elevational view with the upper doors in open position and center doors in closed position.

Fig. 3 is a side elevation with all of the doors shown in closed position.

Fig. 4 is a top plan view thereof.

I claim:

The ornamental design for a combination refrigerator and food freezing unit, as shown.

ALFRED O. BOYCE.
